2,594,194

OIL SEAL FOR ENGINE STARTERS

Charles S. Metsger, Morris Plains, N. J., assignor
to Bendix Aviation Corporation, Teterboro,
N. J., a corporation of Delaware

Application August 19, 1947, Serial No. 769,425

1 Claim. (Cl. 286—27)

1

This invention relates to oil seals for engine starters, and particularly to a starter of the type including a jaw member having axial movement into and out of engagement with an engine element and rotative movement to rotate the element to start the engine.

When a starter including a jaw having such movement is located normally horizontally with its jaw or baffle end inside an airplane engine crank case, the jaw, and the opening into the starter through which the jaw protrudes, are subject to contact with the engine oil while the engine is running, but, when the plane is normally parked are not subject to contact with the oil.

Such occasional oil contact with a normally horizontal starter, which oil leaks into the starter only when the engine is running, has been severe enough to have caused many suggestions for preventing such leakage, certain of which have been satisfactory after considerable experimentation and trial.

When such starter is to be adapted to have its jaw at its upper end facing upwardly as in the bottom of a crank case of a helicopter engine, the problem of preventing leakage is appreciably more difficult. In such case, the sealing means is subject, not only to oil when the engine is running, but to a head of oil of as much as six inches when the plane is parked, so that, instead of having to take care of only occasional leakage past the jaw, as in former practice, the sealing means hereof is called upon to operate effectively under more difficult conditions, and at all times.

Also, under the more difficult conditions in the case of a starter which is adapted for direct cranking, any usual means for frictionally restraining the jaw against rotation for causing the jaw to advance axially into engagement with the engine jaw, would be more continuously subject to a greater amount of oil tending to reduce its friction holding efficiency.

An object of the invention is to provide novel means for sealing a starter of the axially movable rotatable jaw type when the jaw of the latter is subject to conditions such as under the head of oil aforesaid, but which will also be effective under other conditions of service.

Another object is to provide means of the above-indicated character which may be applied to a standard starter, normally adapted for operation in the horizontal position indicated, which application may be effected with substantially a minimum of change.

Another object is to provide a starter which shall be particularly adapted for employment in a

2

helicopter, as indicated, and in other applications to be benefited by the invention.

Another object is to provide an arrangement wherein a plurality of units, each having combined friction and sealing characteristics, are disposed in tandem at opposite sides of a chamber along the jaw, which units operate not only as sealing means but also as friction means for restraining the jaw against rotation to effect its axial movement engaging it to the engine jaw.

Another object is to provide a device of the above-indicated character which is simple and durable in construction, economical to manufacture, and effective in its operation.

15 The above and other objects and features of the invention will appear more fully hereinafter from a consideration of the following description taken in connection with the accompanying drawing wherein two embodiments of the invention are illustrated by way of example.

In the drawing:

Figure 1 is a side view, generally in section, but having parts in elevation, of a portion of an engine starter embodying the invention in one form;

25 Figure 2 is a view similar to a portion of Figure 1 of a starter embodying the invention in another form.

Referring to Figure 1, the starter illustrated is of a type adapted for direct cranking comprising a housing 10 enclosing a rotatable barrel 12, which is driven by a motor through a speed reducing gear train in a usual manner.

The barrel 12 encloses and is operatively connected to an axially stationary cylindrical nut 14 having a torque limiting disc pack 16 having interlayered discs splined to the barrel and the nut, respectively, which discs are adjusted axially against an end wall 18 of the barrel in predetermined friction relation to each other by springs 35 and a ring nut 22 threaded to the barrel 12 inside the latter.

A screw shaft 24 has long-lead thread relation to the nut 14 inside the latter, and is provided with a spline connection 26 to a jaw member 28 adapted for cooperation with an engine jaw element 30. The member 28 comprises end jaws 29, a hollow cylindrical shank 31, and a transverse inner web 32 intermediate its ends.

45 A meshing rod member 34, extending through an opening in the web 32, is held by a nut 36 in sealed relation to the web, rendering the jaw 28 proof against the passage of oil through the shank. The member 34 has a flange 38, below a flange 40 on the screw shaft 24, which flange 38 is normally biased against the flange 40, by one

end of a spring 42 having its other end pressing against a backing ring 44 held by a lock ring 46 in a groove of the screw shaft 24.

In combination with the above-described elements, the invention comprises a hollow wall baffle 48 comprising annular elements 50 and 52, respectively, nested in spaced relation to the shank 31 and to each other to form a chamber 54 therebetween. The element 50 has a cylindrical intermediate portion 56, a radially inwardly extending flange 58 and a radially outwardly extending flange 60. The element 52 has a cylindrical intermediate portion 62 spaced from the portion 56 therein, a radially inwardly extending flange 64 adjacent to the flange 58 spaced therefrom, and a radially outwardly extending flange 66 adjacent to, but spaced from, the flange 60.

The elements 50 and 52 are held in sealed relation to, and spaced from, each other as by a body 68 to define the chamber 54, and having a drain port 70 adapted to receive a coupling 72 for a conduit leading to a location exteriorly of the starter, such as overboard, to a collector tank, or to a trap from which it is automatically returned to the engine oil system.

Yieldable rubber-like ring units 74 and 76, secured to the flanges 58 and 64, respectively, as by vulcanizing through holes and at opposite sides of the flanges, are each provided with a labyrinth of inner surface grooves next to the shank 31 of the jaw 28 against which they are held, as by garter springs 78 and 80, respectively, there being two of the garter springs 78 and one spring 80, in this instance. The springs 78 are shielded by a cover 82.

The starter is held in position relative to a crank case 84, as by shoulder nuts 85 on studs 86.

In operation, when the barrel 12 is drivingly rotated, it acts, through the discs of the pack 16, to turn the nut 14. With the screw shaft 24 splined by the connection 23 to the jaw member 28, and the latter constrained against rotation by the combined sealing and friction holding units 74 and 76, the first turning of the barrel 12 and the nut 14 causes the screw shaft 24 to advance upwardly, as viewed in the drawing, from the retracted or lower position shown to a position in which it engages the engine jaw 30, subsequent to which, with a usual shoulder on the screw shaft 24 in engagement with a usual shoulder on the nut 14, the jaw 28 drives the jaw 30 to normally start the engine.

When the engine starts, the jaw 30 overrides the jaw 28 against the action of the spring 42, and when the starter motor is deenergized, the jaw 30 cams the jaw 28 in a usual manner back to the retracted position shown. If, for any reason, the engine jaw element 30 abnormally resists turning, or if the engine backfires, the reaction is absorbed in the starter by the pack 16.

The outer unit 74 operates to eliminate as much oil as possible from the intermediate chamber 54, but such oil as enters this chamber flows, as in this instance, by gravity to the outlet 72 for disposal as above indicated.

The structure of Figure 2, in contradistinction

to the structure of Figure 1, in which the meshing rod 34 is fixed and sealed to the jaw 28, is adapted for employment with a hollow cylindrical jaw 100 connected to a screw shaft, corresponding to the screw shaft 14, by a mesh rod 104 extending through an aperture in a partition or web 106 of the jaw 100, which aperture is closed by a seal 108 biased against the web 106 by a spring 110 extending into a recess in the screw shaft.

The jaw 100, in this instance, is rendered proof against the passage of oil through the jaw at the sliding seal 108, as by a tightly press fitted disc or cover 111.

The remaining parts of Figure 2, corresponding to parts of Figure 1, are designated by corresponding reference characters.

Although only two embodiments of the invention have been illustrated and described, various changes in the form and relative arrangements of the parts may be made to suit requirements.

What is claimed is:

A seal for use in an engine starter having a housing including an end portion having an opening therein and a rotatable and axially movable jaw member having a cylindrical shank portion extending through the opening in said end portion, comprising an outer baffle plate secured to said housing and having an inwardly extending circumferential flange, a resilient sealing ring, said sealing ring being affixed at its outer peripheral edge to said circumferential flange and its inner edge forming a wiping contact with said shank portion, a garter spring for biasing said inner edge into contact with said shank portion; an inner baffle plate secured to said housing and having an inwardly extending circumferential flange, a resilient sealing ring, said sealing ring being affixed at its outer peripheral edge to said circumferential flange and its inner edge forming a wiping contact with said shank portion, a garter spring for biasing said inner edge into contact with said shank portion; said inner and outer baffle plates being spaced apart to form a collecting chamber along said shank portion, and oil outlet means from said chamber to provide effective drainage therefrom.
